UNITED STATES PATENT OFFICE.

SEBASTIAN ZIANI DE FERRANTI, OF BASLOW, ENGLAND.

ROLLER-BEARING.

1,131,612.

Specification of Letters Patent.

Patented Mar. 9, 1915.

Application filed October 6, 1914. Serial No. 865,368.

To all whom it may concern:

Be it known that I, SEBASTIAN ZIANI DE FERRANTI, a subject of the King of Great Britain and Ireland, and residing at Baslow, in the county of Derby, England, have invented certain new and useful Improvements in and Relating to Roller-Bearings, of which the following is a specification.

The invention relates to roller bearings and especially to the construction of the rollers themselves.

In order to overcome certain difficulties in the working of roller bearings, believed to be due to abrasion or other effect caused by the action of steel on steel under concentrated loads, it has been proposed to construct the rollers of other materials of a non-metallic character and it is the object of the present invention to provide a form of roller specially suitable for such materials, but applicable with advantage in certain cases to steel also.

With this object the invention consists of a roller for the purpose indicated constructed of a number of laminae or thin plates of a metallic or non-metallic material held together axially under considerable pressure by appropriate means.

The invention also consists of a roller as set forth in the preceding paragraph, in which the laminae are formed of a material composed of fiber as a basis.

The invention further consists of the rollers and roller bearings hereinafter described or indicated.

Referring to the accompanying drawings which are to some extent diagrammatic:— Figure 1 shows an elevation of a cylindrical roller, while Fig. 2 shows a similar view of a conical roller.

In carrying the invention into effect according to one form as shown in Fig. 1, a central spindle, *a*, running through the roller is screwed at both ends for the reception of the pressure nuts, *b*, *b*. On the spindle, *a*, are threaded a large number of laminae, *c*, *c*, pressed together axially by the nuts, *b*, *b*, it may be in conjunction with washers, *d*, *d*.

Referring to Fig. 2, which shows a form of conical roller, the spindle, *a*, at one end has formed integrally with it a heavy disk or plate, *e*, against which the laminae, *c*, are

forced by the nut, *b*. The spindle, *a*, is preferably cylindrical so that all the central holes through the laminae are the same diameter.

The laminae should fit neatly on the spindle and after being secured in place may be ground or otherwise finished to the exact size required. The washers and nuts should be proportioned so as to be slightly within the effective surface of the laminated portion of the roller, while if desired the nuts may be hexagonal in the first place and subsequently be reduced to the conical forms indicated in the drawings.

As regards material, the laminae may be made of hardened steel or of more or less homogeneous non-metallic substances such as leather or raw hide; or again substances with a definite fibrous structure such as wood veneer may be used in which case it is preferable that the fibers in adjacent laminae should cross one another at an angle. Similarly woven fabric may be used or material having fiber as a basis but with a less definite structure such as felted material or paper in its many forms including parchmentized paper and especially Manila paper.

In some cases the laminae may be of different materials interleaved, but in general I believe the best results are to be obtained by fibrous materials in which a proportion of the fibers at any rate are arranged at right angles to the surface of the roller.

Having now described my invention what I claim as new and desire to secure by Letters Patent is:—

A roller for roller bearings comprising in combination a spindle, a plurality of laminae each provided with a central aperture, said laminae being held on the spindle in juxtaposed relation to one another, retaining means on each end of said spindle bearing against the outer laminae, one of said retaining means being adjustable axially of said spindle.

In testimony whereof, I affix my signature in presence of two witnesses.

SEBASTIAN ZIANI DE FERRANTI.
